VAN SUPERSTRUCTURE

Manfred Block, Toronto, Ontario, and Gordon McWilliams, Malton, Ontario, Canada, assignors to Vistavan Limited, Toronto, Ontario, Canada, a Canadian company

Filed Jan. 7, 1966, Ser. No. 532

Claims priority, application Canada Sept. 3, 1965

Term of patent 14 years

(Cl. D14—3)

FIG. 1

FIG. 2

FIG. 3

FIG. 1 is a perspective view of a van superstructure embodying our new design, viewed from above and from the front and left side thereof;

FIG. 2 is a perspective view of the van superstructure, viewed from above and from the rear and right side thereof; and

FIG. 3 is a side elevation view of the left side thereof. The broken lines are for illustrative purposes only.

We claim:

The ornamental design for a van superstructure, as shown and described.
